UNITED STATES PATENT OFFICE

WALDEMAR J. REINKE, OF CHICAGO, ILLINOIS, ASSIGNOR TO JUSTRITE MANUFACTURING COMPANY, OF CHICAGO, ILLINOIS, A CORPORATION OF ILLINOIS

WIRE-ATTACHING DEVICE

Application filed August 23, 1928. Serial No. 301,685.

This invention has for its object to provide a simple, cheap and efficient device for securing electric wires along the trim of rooms of buildings without injuring the trim or the walls as by driving staples, brads or screws into the same, and which is of such a nature as to permit of its use by unskilled persons to quickly and neatly string lamp-cords and the like in the home along base-boards, under window casings, etc., to thus maintain such cords off the floor and out of reach of brooms, carpet sweepers, vacuum cleaners and the like.

The invention may be variously embodied and in the accompanying drawings, I have illustrated a plurality of embodiments of the same. In the drawings:

Fig. 1 is a fragmentary perspective sectional view showing a wall and trim equipped with wire attaching devices constructed in accordance with the invention.

Fig. 2 is a fragmentary vertical section of the wall and trim shown in Fig. 1 with a device of my invention engaged therebetween.

Fig. 3 is a front elevation of the wire attaching device in its preferred embodiment.

Fig. 4 is a perspective view of the metallic part of the device.

Fig. 5 is a side elevation of the metallic part of the same.

Fig. 6 is a front view of an insulation strip employed.

Fig. 7 is a perspective view of a modified form of construction of the device.

In building construction it is the usual practice to apply the wood or metal trim, such as base-boards, door and window casings, picture moulding, etc. after the plastering of the walls has been completed, the said trim overlapping the plaster and, generally, leaving shallow free spaces between the plaster and the opposed surface of the trim.

The device of this invention is designed to take advantage of this free space by providing a wire engaging substantially semi-cylindrical member 1 having a shank 2, the latter being adapted for insertion in said free space. However, in order that said shank may be firmly held in place in said free space without the use of fastening devices,

I provide for a wedge like engagement of said shank between trim and plaster. This, in the structure shown in Figs. 1 to 5 and 7 inclusive, is obtained by causing the plane of the flat shank 2 to intersect the arcuate formation 1 at some distance from its free end. At the latter I provide a flange or lip 3 which bears upon the wall and slides along the same without scratching or marring the same as the shank 2 is inserted between trim and plaster. During such insertion the shank 2 will be bent as shown in Fig. 2 so as to exert pressure upon the plaster behind the trim and upon the corner of the latter opposed to the plaster, it being understood, of course, that the device is made of a spring metal such as steel, brass or the like.

By reference to Fig. 5 it will be noted that the curved or hook formation 1 of the device is offset outwardly from the outer face of the shank 2 and that the lip 3 at outer end of said formation 1 is offset inwardly from the plane of the other or inner face of said shank 2, these faces being termed "inner" and "outer" with respect to this position on the wall or surface against which the lip 3 bears as shown in Figs. 1 and 2. It will also be noted that the shank 2 is devoid of any securing means such as brads, screws and the like.

Obviously, the shank 2 of the device may be bent to vary the degree of offset of the lip formation 3 from the plane of its inner face to better accommodate the clip to engage in spaces varying in width.

It will be obvious that the recesses 4 of the shank 2 serve to weaken the latter laterally and increase its flexibility at this point. This has been found advantageous aside from the function of said recesses with respect to retaining the strip 5 of insulation in place, in that, in instances where the crack or space receiving the shank 2 is very small, the insertion of the said shank is less resisted and the flexing thereof confined almost entirely to this weakened portion.

The structure of Fig. 7 is very similar to that of Figs. 1 to 5 inclusive in that the arcuate portion 12 terminates in the flat shank 13 from which the spring tongue 14 is struck, the latter being curved between its ends and

having, preferably, its free end opposed to the upper wall of the slot 15 resulting from the striking out of the tongue 14 from the shank 13. Said tongue 14 preferably extends outwardly from the shank to bear upon the trim surface opposed to the plaster while its flat portion bears on the plaster.

I claim as my invention:—

10 A wire engaging clip for electric wire comprising a plane shank devoid of securing means and terminating at one end in a hook formation to receive a wire, said hook formation being offset outwardly from the outer face of said shank and terminating in a lip formation offset inwardly from the plane of 15 the inner face of said shank.
